UNITED STATES PATENT OFFICE

WILLIAM N. THORNBURGH, OF CHICAGO, ILLINOIS

DUST GUARD FOR JOURNAL BOXES

Application filed January 30, 1922. Serial No. 532,562.

This invention relates to improvements in dust guards for journal boxes and its purpose is to provide a simple and improved device having great efficiency in operation. The principal object of the invention is to provide a dust guard provided with a resilient washer adapted to maintain contact with the car axle. A further object is to provide a laminated wooden dust guard comprising resilient means for securing and maintaining contact with the car axle. A further object is to provide a journal box comprising a dust guard designed to permit relative movement of the car axle with respect to the journal box without causing damage to the dust guard. Other objects relate to various features of construction and arrangement which will appear more clearly hereinafter.

The nature of the invention will be understood from the following specification taken with the accompanying drawings, in which one embodiment is illustrated. In the drawings—

Figure 1 shows a longitudinal vertical section through a journal box and dust guard embodying the principles of the present invention, illustrating the relation of these parts to the car axle; Fig. 2 shows an end elevation of the dust guard looking toward the left, as viewed in Fig. 1; Fig. 3 illustrates a side elevation of the dust guard; and Fig. 4 shows a detail vertical section of the lower part of the dust guard slot, illustrating the relative positions of the parts; Fig. 5 shows the detail sectional view on the line 5—5 of Fig. 2 looking in the direction of the arrows.

Referring to the drawings, the invention is illustrated in connection with the journal box 10, having the usual cover 11 on one end wall thereof and double flanges 12 and 13 forming the other end wall and spaced apart to provide a vertical dust guard slot 14, which is open at its upper end to receive a dust guard 15. The flanges 12 and 13 have openings 16 and 17 therethrough respectively to receive the car axle 18, which is reduced in diameter at 18^a within the dust guard, and still further reduced in diameter at 18^b, which latter portion contacts with the jour-

nal brass 19 mounted on the bearing 20 secured in the upper part of the journal box.

The dust guard formed according to the present invention comprises a plurality of wooden laminations 21, preferably five or more in number, which are secured together by waterproof glue, or the like, the grain of the wood in each lamination being extended substantially at right angles to the grain of the wood in the adjacent lamination, so that greater strength is imparted to the composite structure and the warping of the dust guard prevented. The wooden lamination toward the outer end of the journal box is undercut as shown at 22 and a leather washer 23 is secured in this annular recess by nails 24 or the like, these nails preferably extending through the laminations as shown in Fig. 4 in order to secure them more firmly together. The leather washer 23 is preferably rather stiff and should have a considerable resilience so that the portion 23^a thereof which is bent inward, maintains a tight contact with the annular reduced portion 18^a of the car axle. The parts are so proportioned that the thickness of the floating washer 23^a, plus the distance 25 between the lower edge of the dust guard and the wall of the dust guard slot, is less than the distance 26 between the car axle and the adjacent edges of the flanges 12 and 13, so that when the car axle has relative movement with respect to the journal box, as for example, when the car is stopped suddenly, the axle will come in contact with the edges of the flanges 12 and 13 before the dust guard is crushed between the axle and the walls of the dust guard slot. This construction relieves the dust guard of all unusual strain and it is found that the guards constructed according to the principles of this invention are very durable in practice and maintain a tight closure at the inner end of the journal box.

As a further means of insuring a tight contact between the leather washer and the part 18^a of the car axle, a pair of pressure members 30 are mounted on opposite sides of the axle so that when the car is stopped suddenly the tendency of the car axle to move longitudinally of the car and thus destroy the contact

of the leather washer will be overcome by these pressure members which are mounted to move in a horizontal plane. These members have pins 31 projecting therefrom into 5 recess 32 which are formed in the laminations of the dust guard as shown in Fig. 2, and springs 33 mounted in these recesses are adapted to force the members 30 toward the car axle and thus maintain the leather washer 10 in contact therewith.

Although I have shown and described one form of the invention for the purpose of illustration, it is understood that it may be constructed in various other embodiments 15 without departing from the scope of the printed claims.

I claim:

1. A dust guard for journal boxes comprising a rigid unitary structure formed of a 20 plurality of similar wooden laminations having an aperture therethrough to receive the car axle, an annular resilient leather washer having a portion thereof seated against one side of said laminated structure and having 25 an annular flange turned inwardly within said opening and adapted to maintain contact on its lateral side with the peripheral surface of the axle, and securing devices extending through said annular washer and 30 through the laminations of said structure for securing all of said parts in assembled relation.

2. A dust guard for journal boxes comprising a laminated member having an aperture therethrough to receive the car axle, a 35 resilient annular washer secured to one side of said member and having an inturned annular flange adapted to contact with the annular surface of said axle, curved pressure members located on opposite sides of said 40 axle on the outer side of said inturned flange of said washer, pins extending radially outward from said pressure members, said laminated member having recesses to receive said 45 pins, and coil springs mounted inside of said recesses around said pins for forcing said pressure member radially inward to maintain said resilient washer in contact with said axle.

WILLIAM N. THORNBURGH.
